CLAIM

The ornamental design for compost container, as shown and described.

DESCRIPTION

FIG. 1 is a top perspective view of a composter container showing our new design;

FIG. 2 is a front elevational view thereof, the rear elevational view being a mirror image of that shown;

FIG. 3 is a side elevational view thereof, the opposite side elevational view being a mirror image of that shown; and,

FIG. 4 is a top plan view thereof.

The undisclosed bottom view is plain and unornamented.

FIG.1.

FIG. 2.

FIG. 3.

FIG.4.
